5 Claims. (Cl. 178—44)

Many instances are met with in practice where an arrangement which presents symmetry to ground must be coupled to an arrangement which is dissymmetric to ground, or vice versa. A case like that arises, for example, when the output end of a push-pull scheme must be put in coupling relation with a load resistance, one end of which is earthed; or where a symmetrical antenna, say, a dipole antenna, is to be connected with a dissymmetric feeder line, say, a concentric or co-axial energy line. In all of these cases it is known in practice to branch off conductors which have potentials symmetric to ground by way of connecting lines of correspondingly dissimilar electrical length, from a common potential point of the dissymmetric arrangement. But the identical result is securable by a far simpler scheme, that is, quasi-stationary means. According to the invention, in an arrangement designed to couple a symmetric arrangement to a dissymmetric arrangement, a network of negligible internal resistance is provided between the dissymmetric arrangement and one-half of the symmetric arrangement adapted to turn the potential an angle of 180 degrees, whereas the other half of the symmetric arrangement is directly united with the dissymmetric one. Preferably the connecting network consists of a T type mesh in which the impedance of the series arms is of inverse sign and twice the absolute value of the impedance of the cross arm or element.

In what follows the operation of the invention shall be explained in greater detail by reference to the drawing in which Figure 1 shows a schematic representation of the invention; Figures 2 and 3 show filter meshes used in further explanation of the invention, while Figures 4a and 4b show the simplest forms of filter meshes satisfying requirements of the invention; Figures 5a and 5b show modifications of Figures 4a and 4b useful where a nominally symmetric source is not actually so and Figure 6 shows a further embodiment of the invention.

Referring to Figure 1, this first shows a schematic representation of the invention. What is shown here are the two potentials U symmetric to ground, these potentials being intended to operate upon a load resistance R , one end of which is at ground potential. To this end a net-

work T is interposed between one of the sources of potential supply U and the load resistance R . Now, examining a T mesh of the form shown in Figure 2 which comprises two similar series elements $\pm jX$ and the cross arm

$$\pm j\frac{X}{n}$$

where n for the time being any arbitrary number; and considering the said T mesh as a quadripole (four terminal network), there results in the presence of an input potential U an output potential ϵ_0

$$\epsilon_0 = U \frac{j\frac{X}{n}}{j\left(\frac{X}{n} - X\right)} = U \frac{1}{1 - n} \quad (1)$$

The internal impedance Z_i of the equivalent organization is obtained most conveniently by determination of the impedance between the output terminals, with the source of potential U being short-circuited. Thus—

$$Z_i = -jX + \frac{j\frac{X}{n}(-jX)}{j\left(\frac{X}{n} - X\right)} = -jX + \frac{jX}{n-1} = jX \frac{2-n}{n-1} \quad (2)$$

These relations are represented in Figure 3.

Now, in order to make it possible for the two ground-symmetric potentials U to work together upon a joint resistance R , the upper potential U in Figure 1, as already pointed out, while preserving its amplitude, must experience a shift in phase of 180 degrees; in other words, there must be

$$\epsilon_0 = -U \quad (3)$$

This will be readily the case, as can be seen from the foregoing formulas if $n=2$. In this instance, also the internal impedance, as follows also from Formula 2 is equal to zero with the result that also a combination of inverse sign of X results in the identical effect. In Figures 4a and 4b the two simplest forms of a phase reversing mesh according to the invention are represented, the impedances of the series arms in Figure 4a being of negative sign, while in the case of Figure 4b they have a positive sign. Beyond these instances, of course, there are many other combi-

nations of T or π type meshes designed to fulfill the same purpose and which therefore come within the scope and the spirit of the present invention.

If the two potentials U are not of like size from the outset, then as demonstrated by Equation 1, any other, greater or smaller value of U may be obtained by choosing for n a value other than 2. The remaining internal reactance of the circuit organization which flows from Formula 2 can at any time be cut down to zero level by choosing a suitable dimension for the last series arm of the T mesh. Inasmuch as n must always be greater than unity for the purpose of phase reversal, this series element is able to change only its size, but never its sign. Thus, for instance, it can not change from a capacity into an inductance. What is, moreover, necessary as a general rule is to derive from the feeding potential only active (watt) current. Investigation of the direct graphic representation Figure 4a and Figure 4b shows that this problem is fulfillable by a reactance of the same size as the cross arm connected directly in parallel relation to the potential U . Presupposing equal potentials U , symmetric to ground, there results a circuit arrangement for the network T to be incorporated in Figure 1 of the kind represented in Figures 5a and 5b.

The invention has been described in connection with a dissymmetric consumer or load which is fed from a symmetric source of potential supply, though it will be understood that, as already pointed out above, the connections between load and potential source may be exchanged or reversed with the result that, for instance, also the connection between a symmetric transmitting aerial and a dissymmetric feeder lead is made feasible by using the basic idea of the invention.

Arrangements of the kind hereinbefore described may be used to advantage also if, for some practical reason, say, with a view to a reduction of energy of power, temporarily only one potential U , that is, for instance, only one-half the number of tubes is worked with. An arrangement of this kind is illustrated in Figure 6. Here the two tubes R_1 and R_2 work upon the common and joint load resistance R , the potential of tube R_1 , according to the invention, being turned an angle of 180 degrees by providing the network. In this circuit scheme it is readily feasible to cut off one of the two tubes R_1 or R_2 . It is of advantage to disconnect the tube R_2 , for in this case the load is supplied capacitively from the inductive branch, and this curtails the harmonics to an appreciable degree. Because of the presence of the reactance $+jX$ between the plate and the upper voltage divider, the plate load of tube R_1 will always be purely ohmic in nature, regardless of the size of the load R .

I claim:

1. Circuit organization adapted to establish coupling relations between a radio frequency arrangement which is symmetric to ground and a dissymmetric arrangement, with the characteristic feature that between the dissymmetric arrangement and one-half of the symmetric arrangement there is interposed a network causative of a phase shift of 180 degrees and inherently possessing a vanishingly low internal resistance, 70 while the other half of the symmetric arrangement is directly connected with the dissymmetric arrangement, said network consisting of a T type mesh having a pair of series reactances and a

shunt reactance, the impedance of each of the series arms thereof compared to the impedance of the shunt reactance being twice the absolute value and of opposite sign.

5 2. A circuit organization as claimed in claim 1, with the characteristic feature that in said T type mesh the impedance of each of the series reactances compared to that of the shunt reactance is twice the absolute value thereof and of opposite 10 sign and a second shunt reactance is connected across the first named one half of the symmetric arrangement.

15 3. A circuit organization adapted to establish coupling relations between a radio frequency organization having a pair of terminals adapted to be symmetrically energized with respect to a third terminal of fixed potential and a radio frequency organization having one terminal adapted to be energized with respect to another terminal of 20 fixed potential comprising a direct connection from one of said pair of terminals to said one terminal, a pair of series connected reactances between the other of said pair of terminals and said one terminal and a third reactance connected 25 from the junction of said pair of reactances to said terminals of fixed potential, the value of each of said series reactances being numerically equal to twice that of the third reactance and of opposite sign.

30 4. A circuit organization adapted to establish coupling relations between a radio frequency organization having a pair of terminals adapted to be symmetrically energized with respect to a third terminal of fixed potential and a radio frequency organization having one terminal adapted to be energized with respect to another terminal of 35 fixed potential comprising a direct connection from one of said pair of terminals to said one terminal, a pair of series connected reactances between the other of said pair of terminals and said one terminal, a third reactance connected from the junction of said pair of reactances to said terminals of fixed potential, the value of each of said series reactances being numerically equal to twice that of the third reactance and of opposite sign and a fourth reactance connected from the other of said pair of terminals to said third terminal, said fourth reactance having a value equal to that of said third reactance.

40 5. A circuit organization adapted to establish coupling relations between a radio frequency source having a pair of terminals symmetrically energized with respect to a third terminal of fixed potential and a radio frequency load having one 45 terminal adapted to be energized with respect to another terminal of fixed potential comprising a direct connection from one of said pair of terminals to said one terminal, a pair of series connected reactances between the other of said pair of terminals and said one terminal, a third reactance connected from the junction of said pair of reactances to said terminals of fixed potential, the value of each of said series reactances being numerically equal to twice that of the third reactance and of opposite sign and a fourth reactance connected from the other of said pair of terminals to said third terminal, said fourth reactance having a value equal to that of said third reactance.

50 6. A circuit organization adapted to establish coupling relations between a radio frequency source having a pair of terminals symmetrically energized with respect to a third terminal of fixed potential and a radio frequency load having one 55 terminal adapted to be energized with respect to another terminal of fixed potential comprising a direct connection from one of said pair of terminals to said one terminal, a pair of series connected reactances between the other of said pair of terminals and said one terminal, a third reactance connected from the junction of said pair of reactances to said terminals of fixed potential, the value of each of said series reactances being numerically equal to twice that of the third reactance and of opposite sign and a fourth reactance connected from the other of said pair of terminals to said third terminal, said fourth reactance having a value equal to that of said third reactance whereby the resultant impedance across the other of said pair of terminals and said third terminal is purely ohmic, regardless of the impedance of said radio frequency load.
